UNITED STATES PATENT OFFICE.

ANTHONY GEORGE LYSTER, OF LIVERPOOL, ENGLAND.

HOPPER AND VALVE FOR HOPPER-DREDGERS.

SPECIFICATION forming part of Letters Patent No. 520,210, dated May 22, 1894.

Application filed December 30, 1893. Serial No. 495,231. (No model.) Patented in England April 23, 1892, No. 7,676.

To all whom it may concern:

Be it known that I, ANTHONY GEORGE LYS-
TER, a subject of the Queen of Great Britain,
residing at Liverpool, in the county of Lan-
5 caster, England, have invented a new and use-
ful Improvement in Hoppers and Valves for
Hopper Dredgers or Barges, (for which I have
obtained a patent in Great Britain, No. 7,676,
bearing date April 23, 1892,) of which the fol-
10 lowing is a specification.

Figure 1 is a longitudinal vertical section.
Fig. 2 is a transverse vertical section, and
Fig. 3 a plan of an improved hopper and valve
under my invention and Figs. 4 and 5 are ver-
15 tical sectional views of modified forms.

In the drawings, in which similar letters
indicate corresponding parts, *a* are the walls
of the hopper or receptacle for containing the
dredged matter or spoil.

20 *b* is part of the framework of a barge or
dredger.

c is the deck of the barge.

25 *d* is an annular valve closing against a seat
e around the discharge opening *f* in the bot-
tom of the barge or dredger. From the said
valve a cylindrical jacketed or double walled
30 stem *g* is carried upward above the deck of
the barge or dredger through the dredged
matter or spoil. The valve *d* is provided with
guides *h* which fit freely around a spindle *i*
35 secured at its upper end to a frame *j* carried
by crossbeams *k* on the barge and at its lower
end to a bearing *l* secured to the sides of the
discharge opening *f*.

40 *m* is a rack secured to the top of the valve
stem *g* and engaging with worm and wheel
gearing *n* carried by frame *j* and beams *k*.
The jacketed valve stem *g* has the outer wall
made with perforations *o* therethrough.

45 *p* is a flexible pipe connected to the space
between the double walls of the valve stem
and to the water supply pipe *q*, so that water
may enter the space between the walls of the
valve stem and pass out through the perfora-
tions so as to lubricate the outer surface of
the valve stem and allow of its being easily
raised and also to assist in washing down and
discharging the dredged matter or spoil when
the valve is open.

50 *r* is a water supply pipe near the top of the
hopper, provided with nozzles *s* which direct
water down the inner surface of the hopper

or receptacle and so lubricate it and facilitate
the discharge of the dredged matter or spoil.
The hopper or receptacle may be made with 55
double walls like the valve stem, the inner
one being perforated and the space between
being connected to a water supply, but this
is more costly without an equivalent increase
of efficiency.

60 *t* is a water supply pipe near the bottom of
the hopper or receptacle provided with noz-
zles *u* which admit jets of water into the hop-
per or receptacle so as to propel the dredged
matter or spoil toward the opening *f*. The 65
pipes *t* are connected to a main or tank and
are provided with taps by which the water is
shut off and supplied as required. As many
hoppers or receptacles are arranged in the
70 barge or dredger as are found convenient.

When it is desired to discharge a hopper,
water is allowed to flow through the perfora-
tions *o* over the surface of the valve stem and
the valve is then readily raised by actuating
the worm gear, after which, water is caused 75
to flow through the nozzles *s* so as to lubricate
the surface of the hopper or receptacle and
free the dredged matter or spoil therefrom,
and through the nozzles *u* to force the dredged
matter or spoil out of the opening *f*.

80 In the modified construction of Fig. 4, the
stem *g* of the cylindrical valve *d* is carried by
external guides *h*. The said valve stem *g* is
in the form of a closed chamber having per-
forations *o*, and water is caused to flow into 85
the valve stem and out of the perforations
through the sliding pipe *p*. The valve is here
shown provided with a balance weight *v* so
that it may be readily raised and lowered by
hand or otherwise. The upper pipe *r* of Figs. 90
1, 2 and 3 may be dispensed with as shown
and the dredged matter or spoil moved by
water passing through the lower pipe *t*, only.

Either of the above forms of valve may be
constructed in the form of an inverted trun- 95
cated cone.

100 Fig. 5 is a vertical section of a modification
of apparatus in which a conical perforated
valve *d* is used instead of a cylindrical valve.
The said valve is provided with a hollow stem
g which may move freely in guides *h*. The
upper end of the said stem is connected to a
flexible pipe *p* through which water flows into
the valve and out through the perforations *o*.

The said stem g is also connected by rods x to the piston of a hydraulic cylinder y by which the said valve may be raised and lowered. The said cylinder and operating mechanism is of any usual type.

z is a wedge for preventing the valve from rising owing to the pressure of water beneath.

It will be obvious that many modifications may be made without departing from the main features of my invention.

I claim—

1. A hopper or receptacle, having an opening in its bottom, a hollow perforated valve arranged to close said opening, and means for forcing a fluid outwardly through the perforations in order to interpose a fluid film between the valve and the material contained in the hopper; substantially as described.

2. A hopper or receptacle, having a valved bottom outlet, a series of jet openings in the perimeter of the valve thereof, and means for forcing water through said openings in order to interpose a film of water between the hop-

per and the contained material; substantially as described.

3. A hopper or receptacle, having a valved bottom outlet, a series of jet openings in the lower portion of the valve thereof, and means for forcing water through said openings to force out the contained material; substantially as described.

4. A hopper or receptacle, having an opening in its bottom, a hollow perforated valve arranged to close said opening, means for forcing a fluid outwardly through the perforations, a series of jet openings around the perimeter of the hopper, and means for forcing a fluid therethrough; substantially as described.

In testimony whereof I have hereunto set my hand this 15th day of December, A. D. 1893.

ANTHONY GEORGE LYSTER.

Witnesses:

JAMES JOHNSON,
JNO. GROCOTT.
